DISPLAY CARTON

Gerald P. Hull and George S. Shields,
Tupper Lake, N. Y.

Application January 17, 1947, Serial No. 136,216

Term of patent 14 years

(Cl. D80--5)

To all whom it may concern:

Be it known that we, Gerald P. Hull and George S. Shields, citizens of the United States of America and residents of Tupper Lake, in the county of Franklin and State of New York, have invented a new, original, and ornamental Design for a Display Carton, of which the following is a specification, reference being had to the accompanying drawing, forming part thereof.

In the drawing:

Figure 1 is a top plan view of a display carton, showing our new design;

Figure 2 is a side elevational view thereof;

Figure 3 is a central vertical section thereof as taken on the line 3—3 of Figure 1;

Figure 4 is a bottom plan view thereof as it appears without the wooden spoons shown in dotted lines in Figure 1; and

Figure 5 is an end elevational view thereof.

The portions of the drawing shown in dotted lines are for illustrative purposes only.

We claim:

The ornamental design for a display carton, substantially as shown and described.

GERALD P. HULL.
GEORGE S. SHIELDS.
